UNITED STATES PATENT OFFICE

161,977

FRUIT PICKER

Anna V. Wagner, Chicago, Ill.

Application March 8, 1950, Serial No. 8,393

Term of patent 7 years

(Cl. D22—3)

To all whom it may concern:

Be it known that I, Anna V. Wagner, a citizen of the United States, residing at Chicago, in the county of Cook and State of Illinois, have invented a new, original, and ornamental Design for Fruit Picker, of which the following is a specification, reference being had to the accompanying drawing, forming part thereof, in which—

Fig. 1 is a side elevational view of the fruit picker, showing my new design,

Fig. 2 is a front elevational view, and

Fig. 3 is a top plan view thereof.

I claim:

The ornamental design for a fruit picker, substantially as shown.

ANNA V. WAGNER.
